UNITED STATES PATENT OFFICE

163,754

PREFABRICATED, MULTIPLE-UNIT UTILITY
CABINET OR THE LIKE

**Donald T. Houpt, Minneapolis, Minn., assignor to
Boeing Airplane Company, a corporation of
Delaware**

Application January 31, 1950, Serial No. 7,589

Term of patent 14 years

(Cl. D33—19)

To all whom it may concern:

Be it known that I, Donald T. Houpt, a citizen of the United States, residing at Minneapolis, in the county of Hennepin, and State of Minnesota, have invented a new, original, and ornamental Design for a Prefabricated, Multiple-Unit Utility Cabinet or the like, of which the following is a specification, reference being had to the accompanying drawings, forming part thereof.

Figure 1 is a perspective view of one side of a prefabricated, multiple-unit utility cabinet, showing my new design.

Figure 2 is a similar perspective view thereof viewed from the same side with parts in different adjusted positions.

Figure 3 is a perspective view thereof viewed from one end of the opposite side.

Figure 4 is a perspective view thereof viewed from the other end of such opposite side and showing parts in different adjusted positions.

Figure 5 is a transverse sectional view thereof looking downward.

I claim:

The ornamental design for a prefabricated, multiple-unit utility cabinet or the like, substantially as shown.

DONALD T. HOUPT.
